His Attorney.

UNITED STATES PATENT OFFICE.

WILLIAM C. WHITE, OF SCHENECTADY, NEW YORK, ASSIGNOR TO GENERAL ELECTRIC COMPANY, A CORPORATION OF NEW YORK.

RESISTANCE-UNIT TERMINAL.

1,394,055.

Specification of Letters Patent.

Patented Oct. 18, 1921.

Application filed March 15, 1920. Serial No. 365,830.

To all whom it may concern:

Be it known that I, WILLIAM C. WHITE, a citizen of the United States, residing at Schenectady, in the county of Schenectady, 5 State of New York, have invented certain new and useful Improvements in Resistance-Unit Terminals, of which the following is a specification.

The present invention relates to conductors of high resistivity and comprises a novel 10 current conveying terminal whereby conductors of this type may be conveniently and efficiently connected in circuit.

It has been suggested heretofore to reduce 15 the resistance of the terminals of resistors by dipping the resistors in carbonizable material and baking it at carbonizing temperature. This method is not always applicable, especially when the resistors consist 20 largely of close-grained vitreous material, such as porcelain.

In accordance with my invention, the resistor is treated with a suspension of conductive material so finely divided as to penetrate 25 into the pores of a surface layer of the resistor as well as to superficially coat the same. I preferably provide a terminal thus coated with a coating of metal, preferably by winding the same with wire.

30 The accompanying drawing illustrates in perspective one embodiment of my invention.

The rod 1 consists of a vitreous material, such as porcelain containing in solution a 35 conductive material, as for example, red oxid of iron. Although my invention may be applied to various vitrifiable ceramic resistances, I may mention in particular a resistor consisting of about 60 parts of a porcelain 40 composition and 40 parts red oxid of iron, as being adapted to illustrate the class of material to which my invention is applicable. This mixture is squirted in stick form, dried and fired in an ordinary porcelain kiln at temperatures of about 1340 to 1370 degrees C. Resistors of this particular type do not constitute a part of my present invention, and are described and claimed in the copending application, Serial No. 50 365,738 filed by Elmer E. F. Creighton.

In order to provide terminals for resistance bodies of the above described class, the finished resistors are dipped in a suspension of finely divided graphite or equivalent

conductive material, which preferably has 55 been reduced to such a fine state of subdivision that the particles are in the colloidal state. For example, I may dip the ends of the resistance stick 1 into a graphite composition known as "aquadag". I understand 60 this term to designate suspensions of graphite of colloidal fineness in water. The suspension of graphite penetrates the surface layer only of the resistance material. The article thus treated is allowed to dry and the 65 excess is then wiped off, leaving at the ends 2 and 3 a glossy black surface resembling pure graphite. The surface film of graphite is of relatively high conductivity. In order to protect this film from mechanical 70 injury it is covered with a layer of metal. As shown on the drawing, a convenient way of covering the graphite contact surfaces is to wind them with a layer of closely coiled wire 4, 5, consisting of brass, copper, nickel, 75 or the like. The electrical connection to the metal contacts 4, 5 may be made by usual spring clips 6, 7, mounted upon an insulating base 8.

What I claim as new and desire to secure 80 by Letters Patent of the United States is:—

1. An electrical conductor comprising a vitreous material, a conductor distributed therethrough and containing at the surface portions thereof conductive material of colloidal fineness of subdivision constituting 85 current conveying terminals.

2. An electrical conductor comprising porcelain and a conductive oxid of a metal and containing at the surface portions thereof 90 finely divided graphite and a layer of wire wound on said graphite-filled portions.

3. An electrical conductor comprising a solution of oxid of iron in porcelain having the terminal surface layers impregnated 95 with graphite of a fineness of subdivision equal to that of colloidal graphite and a layer of metal inclosing said terminal surfaces.

4. A conductor of high resistivity comprising a rod of ceramic composition containing a conductive material, a surface layer of aquadag on the terminals of said rod and a layer of wire wound on said terminals over said surface layer. 100

In witness whereof, I have hereunto set my hand this 28th day of February 1920.

WILLIAM C. WHITE.
